(57) **CLAIM**

The ornamental design for a shingle, as shown and described.

DESCRIPTION

FIG. 1 is a top perspective view of an embodiment of a shingle;

FIG. 2 is a top view of the embodiment shown in FIG. 1; FIG. 3 is a bottom view of the embodiment shown in FIG. 1;

FIG. 4 is a left side view of the embodiment shown in FIG. 1;

FIG. 5 is a right side view of the embodiment shown in FIG. 1;

FIG. 6 is a rear view of the embodiment shown in FIG. 1; FIG. 7 is a front view of the embodiment shown in FIG. 1;

FIG. 8 is a top perspective view of another embodiment of a shingle;

FIG. 9 is a top view of the embodiment shown in FIG. 8; FIG. 10 is a bottom view of the embodiment shown in FIG. 8;

FIG. 11 is a left side view of the embodiment shown in FIG. 8;

FIG. 12 is a right side view of the embodiment shown in FIG. 8;

FIG. 13 is a rear view of the embodiment shown in FIG. 8; FIG. 14 is a front view of the embodiment shown in FIG. 8;

FIG. 15 is a top perspective view of another embodiment of a shingle;

FIG. 16 is a top view of the embodiment shown in FIG. 15; FIG. 17 is a bottom view of the embodiment shown in FIG. 15;

FIG. 18 is a left side view of the embodiment shown in FIG. 15;

FIG. 19 is a right side view of the embodiment shown in FIG. 15;

FIG. 20 is a rear view of the embodiment shown in FIG. 15; and,

FIG. 21 is a front view of the embodiment shown in FIG. 15. The dashed broken lines are for illustrative purposes only and form no part of the claimed design.

The dashed-dot lines illustrate unclaimed boundary lines.
